UNITED STATES PATENT OFFICE.

HUGH McCABE, OF LAWRENCE, MASSACHUSETTS.

METHOD OF COLD-DISHING SHEET METAL.

1,383,475.

Specification of Letters Patent.

Patented July 5, 1921.

Application filed July 3, 1919. Serial No. 308,514.

To all whom it may concern:

Be it known that I, HUGH McCABE, a citizen of the United States, residing at Lawrence, in the county of Essex and State of Massachusetts, have invented certain new and useful Improvements in Methods of Cold-Dishing Sheet Metal; and I do hereby declare the following to be a full, clear, and exact description of the invention, such 10 as will enable others skilled in the art to which it appertains to make and use the same.

This invention relates to a method of cold dishing sheet metal. The invention has for 15 an object to provide a method for cold dishing sheet metal in which the dish is formed in successive incremental steps. The invention consists in the method hereinafter described and particularly defined in the 20 claims.

In the drawing, Figure 1 represents a portion of the preferred machine in which a metal sheet is dished according to the present method; Fig. 2 is a plan of a portion 25 of a circular plate illustrating diagrammatically the different portions of the plate which are successively depressed; Fig. 3 is an elevation of the plate after being dished.

It is well recognized in boiler shop practice that for some purposes it is very advantageous and desirable to use sheet metal in dished instead of flat form. Whenever the particular piece of sheet metal is to be subjected to pressure as for example the heads 30 of boilers, it is well known that a steel plate of given thickness will withstand much more pressure in a dished rather than flat form. The method usually employed for dishing metal plates for this purpose consists in

40 heating the plate in a muffle furnace to a red heat and then forming the dish in one operation in a very heavy dishing press while the metal is hot. This method of forming dished plates obliges the ordinary

45 boiler man to either order the plates directly from the mill in dished form or on the other hand to ship the flat plate back to the mill to have it dished. Obviously, either procedure makes the cost of the dished

50 plate exceedingly high; and furthermore, often delays construction. For instance, the expense of shipping back a circular steel boiler plate to the mill and having it dished amounts to approximately \$60. The present method eliminates the disadvantages of the former methods and contemplates per-

mitting the formation of dished plates in the ordinary boiler shop and with equipment which is usually found in such shops, at a very small fraction of the expense which 60 would otherwise be incurred.

In Fig. 1 a portion of a press or similar machine is shown, having the usual reciprocating head 10 which may be reciprocated at the will of the operator by usual and 65 well known provisions not shown. The reciprocating head 10 is provided with a ram 12, screwed therein and which is adjustably held in a locked position with relation to the reciprocating head 10 by a lock 70 nut 13. The ram 12 is cylindrical in shape, and is provided with threads 14 which co-operate with corresponding threads in the reciprocating head and of such size that there are four threads to the inch. It will 75 be observed that the ram 12 may be lowered from the reciprocating head 10 and that in this manner the effective stroke of the ram may be increased or decreased.

A circular die 20 co-operates with the ram 80 12 to perform the dishing operation. When it is desired to dish plates which are relatively large in size the circular die 20 has a diameter of 24 inches, and the upper surface thereof is dished out on a curvature of 85 42 inches radius. The stroke of the ram 12 during the dishing operation is adjusted so that the end of the ram just reaches the bottom of the die 20. In order to safeguard the machine, if for any reason the ram 90 should be lengthened out too much, a hole 20 is provided, of sufficient size to permit clearance of the ram, should the latter be forced therein.

In order to dish small plates, it is not 95 necessary to employ a large die, and for this purpose I have found that a die 12 inches in diameter, and whose upper surface is curved on a shorter radius, gives the best results.

100 In the operation of dishing a plate, the ram 12 is first adjusted in the reciprocating head 10 so that when the head is at the lower end of its stroke, the end of the ram 12 projects slightly below the plane of the 105 upper edge of the die 20. The press is then operated to lift the ram out of the die and a flat plate is inserted between the ram and the die in such position that the edge of the plate coincides with the edge of the die 20, 110 and a portion thereof is directly under the ram, as for example the portion 30 in Fig. 2.

The press is then operated to force down the ram and to raise it again into an inoperative position, in this manner depressing this portion of the sheet and producing a circular depression in the plate near its periphery. The plate is then moved until a second portion 31 lies over the die and the operation is repeated. Similar depressions are successively made in this manner in each of the adjacent portions of the plate such as 32, 33, 34, 35, 36, 37, 38, in Fig. 2.

After the portion of the plate near the periphery has been depressed, a second set of portions of the plate 41, 42, 43, 44, 45, 46, 47, 48, are then subjected to a similar cycle of operations producing depressions of the same depth as the first series of depressions. After the completion of the second cycle of operations the plate is moved thereunder so that the central portion of the plate comes under the ram and a central portion 49 is depressed.

The positions of successive depressions with relation to one another are such that the plate is dished in a uniform curve, and after completion of the operation the plate assumes a perfectly formed dished shape, and the irregularities of the individual depressions are blended to form a continuous curvature from near the periphery of the plate to the center.

A sweep is used as a gage in order to obtain the proper curvature, and if in the completion of the initial dishing operation, the curvature of the dish is not sufficient, the complete operation is repeated with the ram 12 lengthened out slightly so as to form deeper individual depressions.

It will be observed that only two operators are needed to dish a plate, one to operate the press and one to hold the plate, so that a ten foot circular plate may be dished in a relatively short time. I have found that such a plate may be dished in from one to two hours, so that the total expense incurred does not amount to more than five dollars which compares favorably with the expense of sixty dollars which dishing at the mill incurs.

While I have described the preferred em-

bodiment of the invention it is not desired to limit the invention, as modifications thereof may be had within the scope of the following claims:

1. The method of cold dishing circular metal plate having the characteristics of boiler plate which consists in successively depressing and stretching different portions of the plate to form a circular dish of uniform curvature, whereby the diameter of the circular plate remains substantially unaltered.

2. The method of cold dishing metal plate having the characteristics of boiler plate which consists in successively subjecting different portions of the plate to the combined stretching and depressing action of a ram and die to form a dish of uniform curvature.

3. The method of cold dishing metal plate having the characteristics of boiler plate which consists in successively subjecting adjacent portions of the plate to the combined stretching and depressing action of a cylindrical ram and a circular die having a dished surface of materially greater diameter than the diameter of the ram, to form a dished plate of uniform curvature.

4. The method of cold dishing metal plate having the characteristics of boiler plate which consists in subjecting different portions of the plate to the combined stretching and depressing action of a cylindrical ram and a circular die having a dished surface of materially greater diameter than the diameter of the ram, said portions being concentrically arranged with respect to the center of the plate and at different distances therefrom.

5. The method of cold dishing metal plate having the characteristics of boiler plate which consists in successively depressing different portions of the plate an equal amount and in such manner as to slightly stretch the material thereof to form a dish of uniform curvature, said portions being arranged to overlap slightly and in circular paths concentrically arranged with respect to the center of the plate.

HUGH McCABE.
